UNITED STATES PATENT OFFICE.

JOHN A. BLACKBURN, OF VAN WERT, OHIO.

MAIL-BAG.

SPECIFICATION forming part of Letters Patent No. 269,560, dated December 26, 1882.
Application filed May 26, 1882. (No model.)

To all whom it may concern:

Be it known that I, JOHN A. BLACKBURN, a citizen of the United States of America, residing at Van Wert, in the county of Van Wert 5 and State of Ohio, have invented certain new and useful Improvements in Mail-Bags, of which the following is a specification, reference being had therein to the accompanying drawings.

My invention has relation to fastenings for 10 mail-bags, pouches, and the like; and the object of the invention is to provide a fastening device that shall be rapidly and expeditiously manipulated, and at the same time simple and cheap in construction, and thoroughly safe and 15 effective in use; and to that end the novelty consists in the construction of the same, as will be hereinafter more fully described, and particularly pointed out in the claims.

In the accompanying drawings similar letters of reference indicate like parts of the invention.

Figure 1 is a view of the mouth of an ordinary mail-bag closed and secured with my fastening. Fig. 2 is a similar view with the fastening unlocked or in position for opening, and Fig. 3 25 a perspective view of the mail-bag open and in position to receive its contents.

A is a mail pouch or bag, the mouth of which is provided with a flap, B, adapted to fold 30 down over the mouth of said bag when it is closed. This flap B has a series of guides or straps, C, in which slides a flexible strap, D, provided with a series of tongues, E. A metallic keeper, F, is hinged to the strap D and 35 serves to lock the strap in its closed position, and it likewise forms the handle by which the strap is operated.

In the face or front of the keeper F is a recess for holding the tag or label e, and when 40 the flap B is folded down on the opposite side, G, a series of staples, H, secured thereto project through said flap and through orifices d in the flexible strap D, so that a sliding motion of the strap causes the tongues E to simultaneously enter the staples H and pass under 45 the straps C. The keeper F is folded down

into the position shown in Fig. 1, and two of the staples H H' pass through the slots h h in the keeper, thus preventing any motion whatever being given to the strap while the keeper 50 is in this position, and as the opening e of the tag-recess is closed by the staple H' adjoining it, it follows that the one operation not only locks the bolt, but also secures the tag in place and prevents tampering with it or its accidental loss during handling.

To open the bag, it is only necessary to raise the keeper and slide it to the left. This practically is a single motion, and it withdraws all the tongues from the staples. Then by simply 60 raising the flap the bag is open and in the position shown in Fig. 3. By simply closing the flap, sliding the strap, closing the keeper, which likewise in practice is a single motion, the bag is fastened, and when the lock is applied to 65 the staple H' it is impossible to tamper with either the mail-matter or the tag-label. It will thus be seen that the device is rapidly and expeditiously operated, which adds greatly to facilities for handling mail-matter at the offices 70 or in transit on the postal cars, and at the same time perfectly preserves its contents.

Having thus fully described my invention, what I claim as new and useful, and desire to secure by Letters Patent of the United States, 75 is—

1. In a mail-bag fastening, the flap B, straps C, and flexible strap D, provided with tongues, in combination with staples H and keeper F, substantially as set forth.

2. In a mail-bag fastening, the flap B, straps C, and flexible strap D, provided with the tongues E, and slots d, and the keeper F, in combination with the staples H, substantially as set forth.

In testimony whereof I affix my signature in presence of two witnesses.

JOHN A. BLACKBURN.

Witnesses:

E. H. BRADFORD,
H. J. ENNIS.
